UNITED STATES PATENT OFFICE.

ALEXANDER HAMILL, OF BALTIMORE, MARYLAND.

STRAINER OR SAND-VALVE.

990,861.

Specification of Letters Patent. **Patented May 2, 1911.**

Application filed September 12, 1910. Serial No. 581,523.

To all whom it may concern.

Be it known that I, ALEXANDER HAMILL, a citizen of the United States, residing at Baltimore, in the State of Maryland, have 5 invented certain new and useful Improvements in Strainers or Sand-Valves; and I do hereby declare the following to be a full, clear, and exact description of the invention, such as will enable others skilled in the art 10 to which it appertains to make and use the same.

This invention relates to improvements in strainers or sand valves, and has for an object the arrangement of means, including 15 spaced disks, formed with depending edges for directing the water downward in order to maintain the space immediately adjacent the valve clear of sand or other obstruction.

Another object of the invention is the arrangement in a sand valve, of a base formed 20 with a cup-shaped interior having a spider construction positioned at the top thereof merging into a threaded stem designed to receive the water guiding disks, spacing 25 means, and tension or retaining means.

With these and other objects in view the invention comprises certain novel constructions, combinations, and arrangement of parts as will be hereinafter more fully de- 30 scribed and claimed.

In the accompanying drawings: Figure 1 is a side elevation of an embodiment of the invention. Fig. 2 is a vertical sectional view through the structure shown in Fig. 1. Fig. 35 3 is a top plan view of the base. Fig. 4 is a top plan view of the center perforated plate. Fig. 5 is an enlarged horizontal section through a disk shaped tension washer, the curvature thereof being exaggerated. Fig. 40 6 is a top plan view of the top plate. Fig. 7 is a section through Fig. 6 on line 7-7.

In constructing a strainer or sand valve embodying the invention the same is arranged with a base having a depending 45 flange or edge, and a plurality of disks mounted above the base but connected therewith, each of which is provided with depending flanges or edges arranged to be substantially parallel with the flange or edge

of the base, so that water passing up through 50 the base will be discharged in one or more sheets in a downward direction around the valve. This will prevent any accumulation of objectionable matter in the vicinity of the valve, and also will avoid the lifting of 55 the filtration bed or displacement thereof from off the strainer. Also by the arrangement of the downwardly extending flange or edge corrosion and filling up of the strainer is avoided, as no foreign matter can easily 60 enter the valve.

In order that the invention may be more clearly understood an embodiment of the same is shown in the accompanying drawings, in which 1 indicates the base having a 65 depending flange or edge 2 inclined at any desired angle, preferably at a sufficient angle for causing the water to discharge in the vicinity of the base so as to keep that immediate vicinity clear of sand or other ob- 70 jectionable matter. Base 1 is provided with a threaded extension 3 and has threaded thereon a washer 4 of some soft metal in order that any corrosion or disintegration of the thread may be avoided by reason of 75 the soft metal fitting into any unevenness of the pipe to which base 1 is secured. This will therefore make a tight joint and nothing can enter at this point to injure the threads, so that the strainer may be re- 80 moved and again applied without injury. The upper part of the base 1 is provided with a cup-shaped portion or recess 5 which is in free communication with bore 6.

Arranged at the upper part of base 1 and 85 extending across the recess 5 is a spider 7 merging into a threaded stem 8 at the center thereof. The bore 6 is directly below threaded stem 8 so that the discharge of water will strike against the stem, and be spread for 90 causing a substantially even pressure throughout recess 5, and in this manner cause an even pressure of water to pass through apertures 9 in plates or disks 10 and 10'. Plates or disks 10 and 10' are pro- 95 vided with depending flanges 11 similar to flange 2. Above plate 10' is provided a solid plate or disk 12 having a depending flange

13 which overlaps or extends beyond the flanges therebeneath. Flanges or edges 13, 11 and 2 are all parallel so as to permit continuous sheets of water to be discharged 5 from the openings between the respective disks. Disks or plates 10 and 10' are sufficiently spaced apart and spaced from base 1 to equalize or substantially equalize the amount of water passing from openings 14, 15 and 16.

10 Plates 10, 10' and 12 are spaced apart by washers 17 which may be of any preferred thickness, and which may be removed and others of different thickness substituted as desired, so as to adjust the size of the discharge openings 14, 15 and 16. Positioned on top of plate 12 is a dish shaped washer 18 surrounding stem 8. Washer 18 is held in position by a tension nut 19 which, pressing against the washer, substantially flattens 15 the same against plate 12, and by this means a continuous tension is brought to bear upon the respective plates for holding the same properly in position, and for preventing any loosening of nut 19.

20 By the arrangement of the base 1 as set forth with a spider and threaded stem extending therefrom, together with spaced washers having depending edges, a device is provided which is quickly and easily taken 25 apart and cleaned and again assembled, and which at the same time permits the free flow of water into the filter without injury to the filter bed as by lifting the same or stirring the same. Also the depending flanges or 30 edges protect the valve itself against the entrance of sand or other matter, whereby the valve is in a certain sense self-cleaning. The flange 13 of plate 12 overhangs the flanges of the other plates and of base 1, so 35 as to protect the same against any pressure from above, and particularly protect the same against sand entering the openings between the washers.

In order to more thoroughly protect the 40 various plates from being bent out of shape, and from having the openings between the flanges closed, the respective plates are each provided with a plurality of depressions 19 of the same thickness as washers 18, or substantially the same thickness. This will effectually prevent any closing up of the openings between the washers so that water may 45 freely flow therethrough and be regulated in volume by the amount of water flowing through bore 6.

Base 1 is provided with a hexagon shaped portion 20 in order to accommodate a wrench for easily applying and removing the strainer whenever desired without injury 50 to any of the parts.

Of course it will be evident that the depressions 19 may be of any desired number, and depth, and also that the hexagon shaped portion 20 may be varied so as to present a

square structure or any other structure desired adapted to receive a tool for applying and removing the valve without injury to the same.

What I claim is:

1. A strainer valve comprising a base 70 formed with a depending flange member, a perforated plate arranged above said base and provided with a depending flange member, a solid plate arranged above said perforated plate formed with a depending 75 flange member, and means connecting said plates together and said plates to said base, said depending flange members directing liquid flowing through said strainer valve in a downward direction.

2. A strainer valve comprising a base formed with a spider having a stem projecting therefrom, a plurality of plates surrounding said stem, and spaced from said base, and tension means engaging said stem 85 for holding said plates in position.

3. A strainer valve comprising a base formed with a hollowed out cup shaped portion, and a depending flange, a plurality of spaced plates arranged above said base, some 90 of said plates being perforated and each of said plates being formed with a depending flange for directing water in a downward direction, said cup shaped hollowed out portion causing a substantially even pressure 95 against said plates.

4. A strainer valve comprising a base formed with a depending flange, a plurality of plates formed with depending flanges, means for spacing said plates apart and in 100 such ratio as to cause liquid from said base to be evenly discharged from between said plates, and means for holding the plates and the base together.

5. A strainer valve comprising a base 105 formed with a depending flange, and a stem projecting therefrom, a plurality of plates arranged above said base and formed with depending flanges arranged substantially parallel with the flange on said base, means 110 for holding said plates spaced apart, and tension means engaging said stem for connecting the plates and the base.

6. A strainer valve comprising a base formed with a threaded extension for securing the same in position, a threaded washer formed of soft metal screwed on to said threaded extension for taking up any unevenness on the device to which the base is connected, a plurality of spaced plates 120 formed with depending flanges arranged above said base, some of said plates being formed with perforations therein, and means for connecting said plates with said base.

7. A strainer valve comprising a base, a 125 plurality of plates arranged above said base formed with depending flange members, the top plate having its flange member over-

hanging the flange members of the remaining plates, means for spacing the plates apart, and means for holding the plates to the base.

- 5 8. A strainer valve comprising a base, a plurality of plates mounted thereon formed with depressions on the periphery for preventing the openings between the plates from being closed, means for spacing the

plates apart, and means for holding the 10 plates to the base.

In testimony whereof I affix my signature in presence of two witnesses.

ALEXANDER HAMILL.
